(57) **CLAIM**

The ornamental design for a cartridge, as shown and described.

DESCRIPTION

FIG. 1 is a top, front, left side perspective view of a cartridge showing a first embodiment of our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a bottom elevation view thereof;

FIG. 8 is a top, front, left side perspective view of a second embodiment thereof;

FIG. 9 is a top plan view thereof;

FIG. 10 is a bottom plan view thereof;

FIG. 11 is a left side elevation view thereof;

FIG. 12 is a right side elevation view thereof;

FIG. 13 is a front elevation view thereof;

FIG. 14 is a bottom elevation view thereof;

FIG. 15 is a top, front, left side perspective view of a third embodiment thereof;

FIG. 16 is a top plan view thereof;

FIG. 17 is a bottom plan view thereof;

FIG. 18 is a left side elevation view thereof;

FIG. 19 is a right side elevation view thereof;

FIG. 20 is a front elevation view thereof;

FIG. 21 is a bottom elevation view thereof;

FIG. 22 is a top, front, left side perspective view of a fourth embodiment thereof;

FIG. 23 is a top plan view thereof;

FIG. 24 is a bottom plan view thereof;

FIG. 25 is a left side elevation view thereof;

FIG. 26 is a right side elevation view thereof;

(Continued)

FIG. 27 is a front elevation view thereof; and, FIG. 28 is a bottom elevation view thereof. All broken lines illustrate portions of the cartridge that form no part of the claimed design. The oblique line shading represents that the surface is transparent, translucent, highly polished or reflective.
